United States Patent Office

Des. 188,152
Patented June 7, 1960

188,152

ROTATABLE DISPLAY STAND AND MERCHANTISING UNIT FOR PENS OR THE LIKE

Gustave A. Trost, San Francisco, Calif., assignor to Micropoint, Inc., Sunnyvale, Calif., a corporation of California

Filed Feb. 27, 1958, Ser. No. 49,833

Term of patent 14 years

(Cl. D80—9)

Fig. 1.

Fig. 2.

Fig. 3.

Fig. 1 is a top perspective view of a rotatable display stand and merchandising unit for pens or the like showing my new design;

Fig. 2 is an enlarged side elevational view thereof;

Fig. 3 is a top plan view of Fig. 2; and

Fig. 4 is a bottom plan view of Fig. 2 on a reduced scale.

I claim:

The ornamental design for a rotatable display stand and merchandising unit for pens or the like, as shown.
